US0D1001833S

(12) United States Design Patent (10) Patent No.: US D1,001,833 S
(45) Date of Patent: * Oct. 17, 2023

(54) DISPLAY SCREEN OR PORTION THEREOF
WITH GRAPHICAL USER INTERFACE

(71) Applicant: Apple Inc., Cupertino, CA (US)

(72) Inventors: Taylor Gerard Carrigan, San Francisco, CA (US); Thalia Echevarria Fiol, Cupertino, CA (US); Bon Min, Seoul (KR); Eric Lance Wilson, San Jose, CA (US)

(73) Assignee: Apple Inc., Cupertino, CA (US)

() Term: 15 Years

(21) Appl. No.: 29/830,589

(22) Filed: Mar. 14, 2022

Related U.S. Application Data

(63) Continuation of application No. 29/750,800, filed on Sep. 16, 2020, now Pat. No. Des. 949,894, which is a continuation of application No. 29/675,836, filed on Jan. 4, 2019, now Pat. No. Des. 898,759.

(57) CLAIM

The ornamental design for a display screen or portion thereof with graphical user interface, as shown and described.

DESCRIPTION

The sole FIGURE is a front view of a display screen or portion thereof with graphical user interface showing the claimed design.

The peripheral dashed broken lines illustrate a display screen or portion thereof, and form no part of the claimed design. All other broken lines illustrate portions of the graphical user interface, and form no part of the claimed design.

1 Claim, 1 Drawing Sheet
